UNITED STATES PATENT OFFICE

2,611,856

ILLUMINATED SUPPORT WITH
LIQUID-HOLDING PAN

John E. Fredin, Los Angeles, Calif.

Application August 13, 1947, Serial No. 768,401

3 Claims. (Cl. 240—2)

1

The present invention relates to bowl supports and stands, and more particularly to supports and stands for melttable articles such as beverage bowls made of ice and the like.

A primary object of the invention is the provision of an attractive yet relatively inexpensive bowl support or stand having means for illuminating a supported article, for example a punch bowl or the like, as well as for collecting any water or liquid that may drip from said article.

Other aims and advantages of the invention will be apparent from a consideration of the accompanying drawings and annexed specification illustrating and describing a preferred construction embodying the invention.

In the drawings—

Fig. 1 is a side elevation of the stand or support illustrated as supporting a punch bowl or the like which is shown partly broken away;

Fig. 2 is a vertical sectional view of the stand or support;

Fig. 3 is a bottom plan view of the cover plate for the pan; and

Fig. 4 is a detail transverse sectional view taken on the line 4—4 of Fig. 3.

Referring to the drawings, the invention comprises a fluid holding pan 10 of suitable material and shape, an illuminating article holder 15 and an apertured cover member 30 for the pan surrounding the article holder.

In the illustrated form, the pan 10 may be of cylindrical shape and of metal having a bottom 11 and sides 12 terminating in an outwardly beaded rim 13. The bottom is preferably formed with a central upstanding article holder support 14 and is preferably cylindrical and of a size to snugly receive an article holder 15 and support it securely and centrally in the pan 10.

The article holder 15 may advantageously be in the form of a cylindrical metal sleeve having outwardly turned rims 16 and 17 at its upper and lower ends, respectively. These beaded rims 16—17 may be and preferably are turned around reinforcing wires 18 to reinforce the edges and prevent distortion thereof. The sleeve 15 may be provided with an inwardly pressed annular bead 19 to provide a support for an annular shelf 20 soldered thereto, as at 21, and which provides a support for a lens 22 disposed over the opening 20a of the shelf 20. The lens 22 may be secured to the shelf 20 in any suitable manner as by cement or putty 23 adjoining an annular flange 24 secured to the shelf 20.

The side wall of the sleeve 15 is provided with an opening 25 and an electrical fitting 26 in-

cluding a light bulb socket for removably supporting a light bulb 27 centrally of the sleeve 15 and below the lens 22 for illuminating the article supported by the sleeve 15. The sleeve 15 is further provided with a series of ventilating openings 28 below the bead and drainage opening 29 immediately above the shelf 20.

A cover member 30 is provided for the pan and preferably consists of a circular disc of suitable material having a central aperture 31 to receive the sleeve 15 and a radial elongation 32 of said aperture to receive the electrical fitting 26. The cover member 30 is provided with a plurality of perforations or apertures 33 and the underside thereof has secured thereto a plurality of supporting feet 34, advantageously in the form of U-shaped straps for supporting the cover above the pan bottom 11.

The stand or support of the present invention is particularly suited for supporting punch bowls and the like, a portion of which is indicated in broken lines in Fig. 1, and which are usually formed with an annular base B. This base is fitted within the upper end of the article supporting sleeve 15.

One type of punch bowl now in popular use consists of a bowl of molded ice, which of course, melts when subjected to normal room or other temperatures above 32° F.

When the stand is used to support such punch bowls and like articles made of ice, any dripping caused by melting ice will drain to the pan 10 either along the outer wall of the sleeve 15 or through the apertures 33 in the cover 30. Any dripping from the base B to the interior of the sleeve 15 will drain out through the drainage opening 29 in the sleeve 15 above the shelf 20. This construction coupled with the fact that the bottom of the sleeve 15 tightly fits the raised support 14 of the pan bottom 11 insures a dry compartment below the shelf 20 and lens 22 in which is housed the illuminating means and electrical connections therefor. The raised article support 14 also serves to securely position the sleeve 15 centrally of the pan.

The stand is not limited in use to supporting bowls or like articles made of ice. For example, a glass bowl or other article may be supported in the sleeve 15, and the cover 30 may serve as a flower holder by filling the liquid compartment of the pan with water and inserting stemmed flowers through the apertures 33 of the cover 30. Many other uses will be apparent to the decorator and housewife.

While I have illustrated and described a pre-

ferred construction embodying the invention, I do not intend to be limited to the details thereof as the scope of the invention is best defined in the appended claims.

I claim:

1. An ornamental stand comprising a liquid-holding pan member formed with a central raised portion, an open-ended sleeve member having one end removably fitting the edges of said central raised portion and extending upwardly therefrom in spaced relation to the walls of said pan member, said sleeve member forming a liquid tight joint with said pan member to divide the pan member into an annular liquid holding compartment and a central compartment, means at the upper portion of said sleeve member providing an article holding member, a partition mounted in said sleeve member below said article holding member and having a light transmitting portion, a drainage opening in said sleeve member above said partition for draining liquid collected thereabove into said pan member, and an illuminating means mounted in said sleeve member below said partition.

2. An ornamental stand and support for a meltable body comprising a liquid holding open topped pan member having a bottom formed with a central raised portion, an open ended sleeve having one end removably fitting said central raised portion dividing said pan into a central watertight compartment and an annular liquid-holding compartment surrounding said central compartment, said sleeve member provided with an intermediate light-transmitting partition, illuminating means mounted in said sleeve member below said partition, the portion of said sleeve above said partition providing an open topped cupped supporting member for a meltable

body, and an annular cover disposed in said pan supported between the bottom and upper open end thereof and surrounding said sleeve, said cover member and cup-shaped supporting member being provided with drainage openings for draining liquids from the meltable body into said pan and outside the watertight compartment within said sleeve.

5. An ornamental stand as defined in claim 2 further characterized in that the light transmitting partition comprises an annular shelf secured to the inner wall of said sleeve and a light transmitting lens secured to said shelf.

JOHN E. FREDIN.
